UNITED STATES PATENT OFFICE.

GEORGE T. HAINES AND BURTON W. SMITH, OF ROCHESTER, NEW YORK, ASSIGNEES TO
MULTIKRAFT INC., OF ROCHESTER, NEW YORK, A CORPORATION OF NEW YORK.

TOY.

1,268,115.

Specification of Letters Patent. Patented June 4, 1918.

Application filed October 2, 1917. Serial No. 194,373.

To all whom it may concern:

Be it known that we, GEORGE T. HAINES and BURTON W. SMITH, both of Rochester, in the county of Monroe and State of New York, have invented certain new and useful Improvements in Toys; and we do hereby declare the following to be a full, clear, and exact description of the same, reference being had to the accompanying drawings, forming a part of this specification, and to the reference characters marked thereon.

Our invention relates to improvements in toys and has for its object to provide an amusement device of the target shooting type, in which the support for the shooting mechanism is preferably connected with the target holder in such a manner that the latter is held in upright position by the former. A further object of the invention is to provide a target shooting device which can be cheaply manufactured, the construction of which is such that the parts may be readily assembled and disconnected to facilitate convenience in packing and shipping. Still another object of the invention is to provide in a combined target holder and shooting mechanism a plurality of superimposed targets, the lowermost of which is displaceable by the projectile hurled by the shooting mechanism, the remaining targets being movable automatically to successively occupy the position from which the last preceding targets were moved. To these and other ends the invention consists in certain improvements and combinations of parts, all as will be hereinafter more fully described, the novel features being pointed out in the claims at the end of the specification.

40 In the drawings:

Figure 1 is a view in perspective embodying one form of the invention;

Fig. 2 is a sectional elevation of the target holder and gun or projectile guiding member, and

Fig. 3 is a view looking at the lower rear portion of the target holder in which the means for temporarily retaining the targets in position upon the holder is shown.

Similar reference characters throughout the several views indicate the same parts.

Referring to the drawings, 10 represents the magazine or target holder which is held in upright position upon the base 11, both the base and holder being notched at the point where they engage each other as shown in Figs. 1 and 2. This construction allows the target holder to be readily inserted upon the base and held thereon without the use of additional restraining means. At the outer end of the base is provided a block 12 adapted to receive the pivot pin bearing 13, preferably rigidly connected with the gun or projectile guide 14 and which, with the pin, is readily removable from the block 12. The gun 14 is provided with a bore or guideway 15 serving to guide the projectile or shot 16 when the same is impelled by the elastic or tension member 17 in the direction of the targets 18 of the holder 10. The free end of the elastic 17 is preferably permanently connected with the projectile 16 while the opposite end is suitably connected with the post or upright 19 secured upon the base 11 at a point intermediate the gun and target holder.

The gun or projectile guide is provided with a longitudinal cut or opening 20 extending from the guideway 15 through the wall of the gun to permit movement of the elastic 17 therethrough, in order that the projectile may be quickly brought to "release" position, as shown in Fig. 2, without having to force it through the barrel of the gun. The term "elastic" is intended, of course, to cover any resilient member which may be found desirable for use in impelling the projectile through or upon the guideway 15. The rear of the target holder is provided with vertically disposed slots or guideways 21 which, at their lower extremities terminate in the enlarged openings 22 opposite the apertures 23 through which the projectile 16 is impelled to strike the targets 18. As each of the lowermost targets is struck by the projectile, the blow is sufficient to drive the same from beneath the superimposed targets through the opening

22 in the back of the holder 10. A guard 24, comprising preferably a member formed of elastic material, is stretched across the face of the openings 22 at the back of the target holder to prevent the accidental discharge of the targets therefrom. The guard is secured to the holder as indicated at 25 or in any other suitable manner.

10 The gun or projectile guide being pivotally mounted, may be aimed at any one of the lowermost targets visible through the apertures 23, and upon releasing the projectile 16 from the position shown in Fig. 2, the same will, on striking one of the targets, cause it to be moved out of supporting engagement from beneath the superimposed targets, which will then drop down, thereby placing the next succeeding target in position to be struck by the projectile at a subsequent shot.

20 While the projectile guide 14 in the present instance is in the form of a gun barrel, it will be understood that other forms of guides may be substituted without departing 25 from the spirit of the invention.

We claim as our invention:

1. A toy comprising a projectile guide having a guideway throughout its length and an opening extending from the guideway through its outer wall, a projectile, and elastic means for impelling the projectile adapted to enter the guideway through said opening when the projectile is placed in the guideway.

35 2. A toy comprising a target holding member, a plurality of superimposed targets loosely mounted therein, the lowermost of which is adapted to be removed to permit the next succeeding target to assume the position of the one removed, and means for 40 striking a blow on said lowermost target to remove the same.

3. A toy comprising a pivoted projectile guide, a plurality of targets spaced from 45 said guide, and a tension member having one end anchored intermediate said guide and said targets and the other provided with a projectile movable upon the guide and arranged to be impelled by the tension member for striking the targets.

4. A toy comprising a shiftable projectile guide, a target holding member provided with a plurality of spaced targets loosely mounted thereon, and a tension member 55 having one end anchored intermediate said guide and said targets and the other end provided with a projectile movable upon the guide and arranged to be impelled by the tension member for striking the targets to disengage them from the holder.

60 5. A toy comprising a shiftable projectile guide, a target holder provided with a plurality of superimposed loosely mounted targets, the lowermost of which is adapted to

register with an aperture in the holder, and 65 an elastic having one end anchored intermediate the holder and projectile guide and the other provided with a projectile movable upon the guide and adapted to be impelled by the elastic for striking the target through 70 the aperture to remove the same from beneath the superimposed targets.

6. A toy comprising a projectile guide, a target holder provided with a plurality of superimposed loosely mounted targets, the 75 lowermost of which is adapted to be removed from beneath said superimposed targets upon receiving a blow, and an elastic having one end anchored and the other provided with a projectile arranged to be impelled upon the guide by the elastic for striking said lowermost target.

7. A toy comprising a target holder having a plurality of superimposed targets mounted thereon, a projectile guide movably mounted in spaced relation with respect to the targets and a tension member arranged to impel a projectile upon the guide in the direction of the targets, the striking of the lowermost target by the projectile serving to release the same to permit the next succeeding target to assume the position of the one last released.

8. A toy comprising a guide member provided with a longitudinal aperture there-through and an opening extending from the aperture to the outer surface of said guide member a target spaced from the guide, and an elastic having one end anchored and the other provided with a projectile, said 100 elastic being movable into the apertured guide through said opening and adapted to impel the projectile in the direction of the target when released under tension.

9. A toy comprising a projectile guide, a 105 target holder spaced from the guide provided with a vertically disposed guideway for receiving a plurality of superimposed targets, the lowermost of which is adapted 110 to register with an aperture in the holder with which said projectile guide is arranged to be aligned and a projectile impelling member co-operating with the projectile guide to direct a projectile into engagement with the lowermost target to remove the same 115 from the guideway.

10. A toy comprising in combination a projectile shooting mechanism and a target holder provided with a plurality of superimposed targets, the lowermost of which is 120 displaceable by the projectile hurled by said shooting mechanism to permit the next succeeding target to move to the position of the one displaced.

11. A toy comprising a projectile guide, 125 a target holder spaced from the guide provided with a vertically disposed guideway for receiving a plurality of superimposed

targets, the lowermost of which is adapted to register with an aperture in the holder with which said projectile guide is arranged to be alined, a guard for temporarily retaining the lowermost target within the aperture and a projectile impelling member coöperating with the projectile

guide to direct a projectile into engagement with said lowermost target to remove the same from the aperture against the restraint of the guard.

GEORGE T. HAINES.
BURTON W. SMITH.
